(57) **CLAIM**

An ornamental design for a slot for multimedia furniture, as shown.

DESCRIPTION

FIG. 1 is a perspective view of a slot design for multimedia tower;

FIG. 2 is a front view of the slot design for the multimedia tower shown in FIG. 1;

FIG. 3 is a side view of the slot design for the multimedia tower shown in FIG. 1;

FIG. 4 is a top view of the slot design for the multimedia tower shown in FIG. 1; and,

FIG. 5 is a bottom view of the slot design for the multimedia tower shown in FIG. 1.

The dashed lines in the drawings represent environmental furniture and form no part of the claimed design.
